CONTROL MECHANISM FOR OUTBOARD MOTORS

Richard C. Heidner, Hartford, and Herman D. Palmer, West Bend, Wis., assignors to West Bend Aluminum Co., West Bend, Wis., a corporation of Wisconsin

Application May 17, 1950, Serial No. 162,459

9 Claims. (Cl. 115—18)

1

This invention relates to improvements in control mechanism for outboard motors.

It is desirable to regulate and control the engine of an outboard motor through manipulation of the handle on the tiller or steering lever. The tiller should be pivoted so that it may be swung from horizontal to vertical positions as desired. It is also the practice to mount the engine so that it has limited reciprocal vibratory motion with respect to the tiller (or the support on which the tiller is mounted) in order that the tiller be shock mounted from the engine vibrations. Heretofore these conditions have prevented the engine from being satisfactorily controlled by the manipulation of the handle on the tiller. The pivoting of the tiller or engine torque vibration adversely affected the satisfactory control of the engine by the tiller handle.

It is an object of this invention, therefore, to provide a control mechanism for the engine of an outboard motor which is operated by the manipulation of a handle on a tiller pivotally carried on the outboard motor and shock-insulated from the engine.

Another object of this invention is to provide a control mechanism for the engine of an outboard motor which is flexible and accurate in operation, not adversely affected by the engine vibration, and comparatively easy to assemble and manufacture.

A still further object of this invention is to provide a control mechanism for the engine of an outboard motor which may be operated both by the manipulation of a handle on a tiller and by a remote control mechanism disconnectibly associated with the tiller mounting.

These objects are obtained by utilizing a motion transfer member which is coaxially arranged with respect to the pivotal mounting of the tiller and is movable longitudinally of such mounting in response to rotational movement of the handle on the tiller to effectuate the movement of the adjustable stator of the engine magneto or other adjustable engine control. This arrangement permits the tiller to freely pivot from horizontal to vertical position without changing the positioning of such motion control member as the result thereof. The motion transfer member is connected to the rotatable engine control by a mechanism which includes a flexible member which permits relative vibrational movement to take place between the engine and the tiller or tiller support without unduly interfering with the operation of the control mechanism. A flexible control cable is detachably rotatably mount-

2

ed on the hub of the pivoted tiller and connects with the motion transfer member so that such member may also be operated from a hand control remote from said tiller.

5 The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawings, in which:

15 Fig. 1 is a view in side elevation with parts broken away for the sake of clarity in illustration, illustrating a control mechanism for an outboard motor embodying the present invention;

19 Fig. 2 is a front perspective fragmentary view of such control mechanism;

20 Fig. 3 is a fragmentary sectional view taken along the axis of the pivotal connection of the tiller;

25 Fig. 4 is a fragmentary sectional view taken longitudinally of the tiller;

Fig. 5 is a fragmentary plan view of the rear of the engine showing the magneto shorting contacts;

30 Fig. 6 is a fragmentary top plan view taken on line 6—6 of Fig. 5;

Fig. 7 is a fragmentary sectional view of the hub of the tiller with the remote control mechanism removed; and

35 Fig. 8 is an enlarged sectional view taken on line 8—8 of Fig. 2.

Fig. 9 is an enlarged fragmentary sectional view taken on the line 9—9 of Fig. 1.

Referring to the drawings by reference numerals, the outboard motor shown in Fig. 1 in its general features is of well-known construction. It has a lower leg 10 which is rotatably supported in a swivel bracket 12 by which the outboard motor is secured to the transom of a boat. The engine 14 is carried at the upper end and has an engine cover 16 removably supported in a cover support 18. The motor and such support are shock mounted (see rubber bushing 11, Fig. 9) with respect to each other and have relative vibratory movement whereby engine shock is not transmitted to the support plate and cover.

40 It is customary to control the speed of outboard motors of this type by advancing or retarding the stator of the magneto and at the same time opening or closing the throttle of the carburetor. Such joint control in the motor herein described is accomplished by the old expedient of utilizing

a cam surface carried on the magneto stator 65 to contact a pivoted bell crank 66 connected to the carburetor throttle lever 70 by a link 68. As the stator 65 is advanced this expedient causes the throttle to gradually open and as the stator is retarded it causes the throttle to gradually close. Hence this invention is concerned primarily with controlling the advancing and retarding of the stator 65 by the rotation of the handle on the steering lever or tiller or by a remotely positioned control lever. It is also a characteristic of this invention that the shorting of the magneto to stop the engine may also be controlled by the rotation of such handle.

The handle 20 is rotatably carried by a tiller or steering lever 22 which is pivoted to the support 18 so that it may be rotated about an axis substantially normal to the drive shaft of the engine. Thus the tiller may be swung from the horizontal position shown in the full line of Fig. 1 to the vertical position indicated by the dotted lines in such figure. To so pivotally mount the tiller 22, a hollow pivot tube 24 having a threaded end is rotatably mounted in a bearing 25 in the support 18 and held against axial outward displacement by lock nuts 26. The pivot tube has a slot 28 in its wall which permits the pinion 38 to enter within such tube and engage with a circular rack 60 carried therewithin. The tiller 22 has a hub 30 which is rigidly fixed on the pivot tube 24 by a set screw 32 which sets in an opening in such tube. The hub bears laterally against the support 18 and prevents axial inward displacement of tube 24. The tiller 22 has at its hub end a bearing 34 which rotatably receives one end of a control rod 36 extending longitudinally of such tiller. The pinion 38 is fixed to such control rod near bearing 34. The outer end of the hub 30 has a recess 40 which in this modification is covered by a tiller cap 42. This recess is utilized in connection with a remote control device to be hereinafter more fully described. A sleeve 44 is rotatably mounted in a bearing 46 mounted intermediate the ends of the tiller 22 and projects beyond the outer end thereof to receive and hold the rubber hand-grip 20. The outer wall of the sleeve near its end is provided with a groove 48 within which fits the end of a thrust screw 50 to retain the sleeve against longitudinal displacement within the tiller and yet permit it to rotate with respect thereto. The interior end of the sleeve has a plug 52 fixed therein into which the outer end of the control rod 36 is secured by pin 54 to prevent relative rotation therebetween. As so constructed, the rotation of the handle 20 will cause a direct and immediate rotation of the pinion 38. It is preferable to put a collar 56 on the sleeve 44 between the end of the tiller 22 and grip 20. This collar is of sufficient breadth to inscribe thereon various indicia, such as the words Fast, Slow, Stop, and Start. The collar may be adjustable so that such indicia may be brought into proper registration with a gauging arrow on the tiller 22. Such registration aids the user in setting the motor control by the turning of the handle 20. It is also preferable to place a bend preventer 58 between the central portion of the control rod 36 and the wall of the tiller 22 to prevent the rod from flexing upwardly under the thrust pressure developed by the pinion 38 as it engages with the circular rack 60.

Rotational movement of the pinion 38 is translated into reciprocal lineal motion by its engagement with a circular rack or motion transfer

member 60 mounted for longitudinal and rotational movement within the pivot tube 24. The inner end of such rack terminates in a flat projection 62 which has an opening therein for receiving and holding the end of a control link 78. With this construction the tiller 22 may be swung to any place within the quadrant between the horizontal and vertical positions shown in Fig. 1 and the pinion 38 will slide around the teeth of the circular rack 60 without causing any motion or adjustment of the rack 60. At any position within such quadrant the handle 20 may be rotated and the circular rack 60 will be adjusted longitudinally in accordance with such rotation.

The lineal motion of the circular rack 60 causes rotation of the adjustable magneto stator 65 by means of mechanism now to be described. As previously pointed out, the engine 14 has rotational torsional vibration with respect to the support 18 and provision is made in the mechanism to be described to permit such relative movement to take place without adversely affecting the adjustment of the magneto stator. To accomplish this a T-shaped control 72 is mounted by stud 74 to bracket 76 secured to the support 18. The vertical leg of such control is connected with the circular rack 60 by a link 78. When as viewed in Fig. 2, the handle 20 is rotated clockwise, the T-shaped control 72 will likewise be rotated in such direction, and vice versa. The ends of the horizontal arms of such control are connected by a flexible cable 80 to the stator 65 so that the clockwise rotation of the T-shaped control will cause a clockwise rotation of the stator, as viewed from the top of the engine, and vice versa. The cable 80 extends around the rear of the stator 65 and rides in a groove 82 cut therein. It is held against sliding movement with respect thereto by a cable clamp 84. To effect an adjustment between the cable and the stator the screw of this clamp may be loosened and the parts slid relatively to each other. The screw when again tightened clamps the cable against further relative movement with respect to the stator. The cable passes substantially vertically upward from the ends of the horizontal arms and passes over fibre pulleys 86 and 87 and extends thence to the groove 82. These pulleys are carried so that the top thereof is substantially parallel with the groove 82 by pulley brackets 88 and 89 secured to the engine 14. Thus the pulleys vibrate as a unit with such engine. However, there is substantial distance between the pulleys and the horizontal arms of the T-shaped control 72 and when the pulleys vibrate with the engine the cable 80 will permit relative movement between the pulleys and the T-shaped control without causing enough movement of the stator 65 to appreciably affect the operation of the engine. Any elongation or shortening of the distance between the points of attachment of the cable to the horizontal arms and of contact with the pulleys 86 and 87, as a result of such relative movement, will be compensated for by a cable spring 90 inserted between the cable and the T-shaped control 72. This spring is of the tension type and is sufficiently strong to transmit normal operating force without elongation and light enough to elongate when the tension increases above that needed for normal operation because of such relative movement. The end of the cable 80 opposite the spring 90 may be anchored to the horizontal arm by a clip 92 designed to facilitate assembly.

In Fig. 2 the parts are shown in the positions

assumed when the engine is operating at slow to medium speed. In order to speed up the engine the handle 20 is rotated in a counter-clockwise direction as viewed in Fig. 2 and as viewed from the left hand side of Fig. 1. This advances the adjustable stator 65 by moving it in a counter-clockwise direction as viewed from the top of the motor causing the spark to be advanced and the throttle opened thus increasing the speed of the engine. In order to slow down the engine the handle 20 is rotated in a clockwise direction. This retards the adjustable stator 65 by moving it in a clockwise direction causing the spark to be retarded and the throttle opening cut down thus decreasing the engine speed.

If the handle 20 is rotated clockwise to its extreme limit of travel the engine will be stopped. This is accomplished by a pair of contacts 94 and 96 positioned on the perimeter of the adjustable stator 65 and insulated therefrom in the usual manner by bushings 98. These contacts are connected by leads 100 and 102 to the primary circuit of the magneto so that when such contacts are interconnected the magneto will be grounded and the engine stopped because of no ignition. To so interconnect such contacts there is fixed to the engine block a shorting contact 104 which has a pair of spaced interconnected metal fingers 106 and 108 arranged to engage the contacts 94 and 96 as the stator 65 reaches its clockwise extreme of travel. The position of such parts is shown in Fig. 5 just before contact is made shorting the magneto. When the engagement occurs between the fingers and the contacts the magneto will be shorted and the engine stopped. Thus the engine speed can be controlled and the engine stopped by the operation of the handle 20. This is a good safety feature particularly with high speed power fuel outboard motors as the operator usually has his hand on the handle for steering the craft.

Sometimes the vibration of engine operation will cause such stator to shift slightly varying the selected speed particularly if the handle 20 is not held. It is therefore desirable to have a friction device for holding the adjustable magneto stator 65 in any of its selected positions. One way of accomplishing this is to mount a friction washer 73 on the stud 74 between the bracket 76 and the control 72 and to place a spring washer 75 on such stud between the locking nut 77 and the control 72. By tightening the locking nut 77, a suitable amount of pressure may be exerted by the spring washer 75 to cause the friction washer to restrain undesirable movement of the control 72 and thus hold the magneto stator in the selected position.

As has been previously explained, the tiller hub 30 is provided with a recess 40 into which a remote control mechanism is removably fitted and connected with the circular rack 60 so that the engine may also be controlled from a part of the boat removed from the tiller 22. The remote control mechanism includes a casing plug 110 which slidably fits within the recess 40 and is held therein for relative rotational movement by a thrust set screw 112 slidable in an annular groove 114 formed in the surface of such plug. Thus the tiller 22 may swing without interfering with such plug. The outer end of the plug 110 is split at 116 and has a bore 118 for receiving the sheathing 120 of a flexible control cable. A screw 122 tightens such split to clamp the sheathing 120 in place. The inner end of such plug has a counter-bore 119 for slidably guiding

a fitting. The flexible control cable has a control wire 124 slidable in the sheathing 120. This wire is provided at its projecting end with a ball or holding member 126 which slips into a lateral opening 128 in a fitting 130 to be disengageably connected with such fitting. The fitting 130 has a stem 132 threaded into the opening 64 in the end of the motion transfer member 60. The flexible control cable may be of any desired length and the outer end of the control wire may terminate in a jaw 134 adapted to be secured to a manual control mechanism of well-known design. To assemble the remote control to the outboard motor, the screw 122 is loosened so that the casing plug 110 may be slid back on to the flexible cable and let the ball 126 project beyond the inner end of such plug. The fitting 130 is securely screwed in the end of the circular rack 132 and the ball 126 is slid laterally of the fitting 130 into the opening 128 to anchor the wire 124 to such fitting. The plug 110 is then slid into the recess 40 with the fitting 130 slidably received in and guided by the counter-bore 119. The screw 122 is thereafter clamped to hold the sheathing 120 in the position as shown. Relative movement between the sheathing 120 and the control wire 124 will slide the circular rack 60 back and forth with the same results as those heretofore explained in connection with the turning of the handle 20. The remote control mechanism may be operated in all positions of the tiller 22 and may be easily removed by loosening the two screws 112 and 122 sliding the plug 110 back to expose the fitting 130 and slipping the ball 126 out of the opening 128 to complete the disconnection.

Although only one embodiment of the invention is shown and described herein, it will be understood that this application is intended to cover such changes or modifications as come within the spirit of the invention or scope of the following claims.

We claim:

1. Control mechanism for an outboard motor having a rotatable engine control, a tiller, and a pivotal connection between said tiller and said outboard motor whereby said tiller may be swung in a vertical plane with respect to said motor, comprising a control handle rotatably mounted on said tiller, a motion transfer member positioned coaxially with respect to said pivotal connection and movable longitudinally thereof, means for imparting longitudinal motion to said transfer member upon rotation of said handle, and motion transmission means between said rotatable engine control and said motion transmission member whereby said engine control is operated upon rotation of said handle in any position of said tiller.

2. Control mechanism as claimed in claim 1 in which said motion transfer member is a circular rack.

3. Control mechanism as claimed in claim 2 in which said means is a pinion rotatable with said handle and intermeshing with said circular rack.

4. Control mechanism for an outboard motor having a rotatable engine control, a tiller, and a pivotal connection between said tiller and said outboard motor whereby said tiller may be swung in a vertical plane with respect to said motor, comprising a control handle rotatably mounted on said tiller, a motion transfer member positioned coaxially with respect to said pivotal connection and movable longitudinally thereof,

means for imparting longitudinal motion to said transfer member upon rotation of said handle, a flexible wire and sheathing control member having the wire connected with said motion transfer member and the sheathing connected with said tiller whereby longitudinal motion may be transmitted to said transfer member by mechanism connected to said sheathing and wire remote from said tiller, and motion transmission means between said rotatable engine control and said motion transmission member whereby said engine control is operated upon rotation of said handle in any position of said tiller.

5. Control mechanism as claimed in claim 4 in which there is a removable plug disconnectible from said tiller and secured to said sheathing and a fitting disconnectible from said motion transfer member and having a socket for receiving a holding member on said wire, and a holding member on said wire removably held in said socket.

6. Control mechanism for an outboard motor having a magneto stator advanceable or retardable by limited rotation thereof comprising means for imparting rotational movement to said stator including a pivoted lever operated by reciprocal movement of an arm thereof, a tiller for said motor, a hollow tubular pivot mounting said tiller to said motor, a control member rotatably and slidably mounted in said tubular pivot and having an end extending therefrom and connected with said arm, and means carried by said tiller and connected with said control member for imparting reciprocal longitudinal movement thereto.

7. Control mechanism as claimed in claim 6 in which said hollow tubular pivot has a slot leading to the interior thereof, and through which said means is operatively connected to said control member.

8. A control mechanism as claimed in claim 6 in which a friction washer and spring washer are inserted on opposite sides of said pivoted lever to frictionally restrain said lever against undesirable rotation thereof.

9. Control mechanism for an outboard motor having a lower leg adapted to be secured to a

boat for pivotal movement with respect thereto about a substantially vertical axis, an engine carried by said lower leg, an engine control carried by said engine for rotation about a substantially vertical axis, a tiller support having rotational torsional vibration with respect to said engine about a substantially vertical axis, and a tiller pivotally carried by said support for rotation about a substantially horizontal axis, comprising 5 a control handle rotatably mounted on said tiller, a lever mounted on said support and spaced vertically from said engine control, means interconnecting said lever and said handle whereby rotation of said handle operates said lever, a sheave carried by said engine in substantial horizontal alinement with said engine control and in substantial vertical alinement with an end of said lever, and a flexible member operatively interconnecting said end of said lever and said engine control and passing over said sheave, there being a substantial length of said flexible member vertically disposed between said sheave and said end of said lever whereby said rotational torsional vibration may take place without undue interference of said control mechanism.
